[57] CLAIM

The ornamental design for a mounting bracket for a specimen cup, substantially as shown and described.

DESCRIPTION

FIG. 1 is a front elevational view of a mounting bracket for a specimen cup showing our new design;

FIG. 2 is a right side elevational view thereof;

FIG. 3 is a top plan view thereof;

FIG. 4 is a bottom plan view thereof; and

FIG. 5 is a rear elevational view thereof.

FIG. 1.

FIG. 2.

FIG. 3.

FIG. 5.

FIG. 4.
